(57)

CLAIM

The ornamental design for a desktop cord holder as shown and described.

DESCRIPTION

FIG. 1 is a top plan view of a desktop cord holder showing my new design.

FIG. 2 is a front elevation view thereof; a rear elevation view is a mirror image thereof.

FIG. 3 is a bottom plan view thereof.

FIG. 4 is a perspective view thereof from the front, top, and right side.

FIG. 5 is a left side view thereof.

FIG. 6 is a right side view thereof; and,

FIG. 7 is a perspective view thereof from the front, bottom, and right side.

The broken lines are included for the purpose of illustrating unclaimed portions of the design and form no part thereof.

1 Claim, 7 Drawing Sheets
